CABINET FOR MAGNETIC DRUMS OR SIMILAR ARTICLE

Robert Van Valkinburgh, Ambler, Pa., assignor to Sperry
Rand Corporation, New York, N.Y., a corporation of
Delaware

Filed May 7, 1963, Ser. No. 74,781

Term of patent 14 years

(Cl. D26—5)

FIG. 1

Des. 196,918

PAGE 2

FIG. 2

FIG. 3

FIG. 1 is a front perspective view of the cabinet for magnetic drums or similar article, showing my new design;

FIG. 2 is a rear perspective view thereof; and

FIG. 3 is a top view thereof.

I claim:

The ornamental design for a cabinet for magnetic drums or similar article, as shown.
